UNITED STATES PATENT OFFICE.

KARL BAUMANN, OF URMSTON, ENGLAND, ASSIGNOR TO WESTINGHOUSE ELECTRIC & MANUFACTURING COMPANY, A CORPORATION OF PENNSYLVANIA.

ELASTIC-FLUID TURBINE.

Application filed June 17, 1924, Serial No. 720,663, and in Great Britain August 2, 1923.

This invention relates to that type of elastic fluid turbine wherein stationary blades or diaphragms are housed in a stator of substantially regular shape formed separately 5 from and located within the turbine casing so that it can expand and contract independently of the latter, the arrangement being such that motive fluid can surround the internal stator and maintain it at substantially 10 the same temperature as the stationary blades or diaphragms so that any expansion or contraction of such blades or diaphragms due to temperature variations will be compensated by equivalent expansion or contraction 15 of the stator in which they are housed.

The invention has for its object to support the internal stator in such manner that it will be maintained substantially concentric with the rotor under all conditions of operation, and to this end consists in the provision 20 of a number of guides which connect the stator with some other stationary part of the turbine and are capable of movement in a radial direction only relative to at least one 25 of these parts. The stator may also be connected in a suitable manner with some part of the turbine which is substantially unaffected by irregular expansion or contraction of the turbine casing.

In one convenient construction, which also 30 serves both to prevent leakage of steam between the turbine casing and the internal stator and to transmit to the former any end thrust set up in the latter, either the stator or 35 the turbine casing is provided with a flange or collar which engages an annular groove or recess formed in the other of these parts and the guides connect the flange or collar with the wall of the groove or recess. Preferably 40 the guides, which may be in the form of pins, project radially through the base of the groove or recess into the annular flange or collar, or vice versa, although where the general construction of the turbine permits 45 of their assembly in such manner they may project longitudinally of the turbine through a side wall of the groove or recess into the flange or collar. These guides, of which there are preferably at least three distributed 50 substantially uniformly around the circumference of the turbine, may be rigidly secured either in the base or wall of the annular groove or recess or in the flange or collar, or, alternatively, they may be capable of free

radial movement only relative to both of these parts.

Where such an arrangement is possible, the radial flange or collar is preferably located at the low-pressure or exhaust end of the internal stator so that fluid pressure acting on the exterior of the latter will exceed that acting on the interior thereof and will tend to hold together the parts into which the stator is divided, and thereby relieve the bolts or studs uniting such parts of certain 65 stresses to which they would otherwise be subjected.

Where the stator is formed in sections, each section is preferably assembled in the turbine casing in the manner set forth above 70 and the several grooves or recesses formed for the reception of the flanges or collars are so disposed relative to the overall dimensions of the internal stator that an annular gap is formed between each pair of adjacent sections through which motive fluid can gain 75 access to the exterior thereof.

In order that the invention may be more clearly understood and readily carried into practice reference will now be made to the 80 accompanying drawings wherein Fig. 1 is a longitudinal section through the top half of a turbine constructed in accordance therewith. Fig. 2 is a similar but fragmentary view illustrating a modification, Fig. 3 is a 85 section on the line III—III of Figs. 1 and 2, and Fig. 4 illustrates a further modification of my invention. In each of these figures certain parts which should appear behind the plane of the section have been omitted to 90 simplify the illustration.

In each form illustrated, the turbine comprises a casing 1, rotor 2, and internal stator of three sections 3, 4 and 5, respectively, in which are housed the blade-carrying diaphragm 6. In Fig. 2 the rotor 2 and sections 3 and 5 and in Fig. 3 the rotor 2 and diaphragm 6 are omitted to avoid unnecessary repetition.

Each section 3, 4 and 5 is provided with an annular flange or collar 7 which engages and is capable of limited radial movement in one of a number of grooves or recesses 8 turned in the interior of the casing 1 and so disposed relative to the overall length of the sections 3, 4 and 5 that an annular gap 9 is formed between each pair of adjacent sections through which motive fluid can gain access to the ex- 100 105

terior of the latter. In the form illustrated by Fig. 1 the flanges 7 are located at the low-pressure ends of the sections for the reason stated above, and the first diaphragm 6 is provided with a spigotted hub or center portion 6^a which is recessed into the gland housing 10 at the high pressure end of the turbine, whereby this diaphragm serves as an additional means of centering the stator section 10. 3. In the form illustrated by Fig. 2 the flanges 7 are located midway of the length of the sections.

When the internal stator is assembled as shown, pins 11 are inserted from the exterior 15 of the casing 1 through holes in the base of each groove or recess 8 into corresponding holes in the flanges 7, covers 12 being then secured in place to close the openings in the casing 1. As shown, these pins are screwed 20 or driven, through clearance holes in the casing 1, into tapped or neat holes in the internal stator. It will be obvious, however, that the method of securing the cooperative 25 relation of the stator and the casing by means of guide pins, in accordance with my invention, may be reversed or modified so long as the pins serve to maintain the internal stator substantially concentric with the turbine axis under all conditions of operation 30 and at the same time prevent rotation of the internal cylinder relative to the casing 1.

In the constructional forms illustrated four pins 11 are employed, two below the horizontal joint at a small inclination to the horizontal, and two in a vertical plane. Any other suitable number and arrangement may, however, be adopted.

As briefly outlined above, where the construction of the turbine permits of such an arrangement, the pins 11 may be replaced by guides which are disposed longitudinally of the turbine and connect a side wall of the groove 8 with the flange 7. Such guides should have parallel sides disposed radially 45 of the turbine and may be secured either to the flange 7 with the parallel radial sides engaging a radial slot in the groove 8. For example, I show in Fig. 4 a guide 15 formed on the flange 7 engaging a longitudinally extending slot 16 formed in the groove 8. It 50 will be obvious, however, that this method may be modified or reversed.

Where the internal stator comprises a single cylinder, it is preferably connected at one 55 end with some part of the turbine which is substantially unaffected by irregular expansion and contraction of the turbine casing. Where a co-acting flange 7 and groove 8 are located at one end of the stator, such connection, which may be effected with the gland or bearing housing by means of an end diaphragm as illustrated in connection with the section 3 of Fig. 1, is preferably arranged at 60 the end remote from such flange and groove.

65 Although the invention has only been illus-

trated in connection with a turbine of the disc type, it is equally applicable to turbines of the drum type.

While I have shown my invention in but two forms, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:—

1. A turbine having an internal stator wherein the internal stator is connected with some other stationary part of the turbine by a number of guides which are capable of movement in a radial direction only relative to at least one of these parts.

2. A turbine as claimed in claim 1, wherein the stator is also connected with some part of the turbine which is substantially unaffected by irregular expansion and contraction of the turbine casing.

3. In a turbine, the combination of a casing having an annular groove provided therein, an internal stator provided with a flange or collar engaging with the groove, and a plurality of radially extending guides cooperating between the flange and the casing and each permitting free relative movement therebetween in a radial direction only.

4. In a turbine, the combination of a casing having an annular groove provided therein, an internal stator provided with a flange or collar engaging with the groove and in spaced relation thereto around the periphery of the flange, and a plurality of radially extending guides arranged around the flange cooperating between the flange and the groove and permitting free relative radial movement only therebetween while maintaining the internal stator concentric with the rotor.

5. A turbine as claimed in claim 4 wherein the radially extending guides are in the form of pins projecting radially through the base of the annular groove in the casing into the flange or collar.

6. In a horizontal turbine, the combination of a casing having an annular groove provided therein, an internal diaphragm carrying stator provided with a flange or collar engaging with the groove and in spaced relation thereto around the periphery of the flange, and at least three radially extending guide pins disposed around the casing and projecting through the casing at the base of the annular groove into the flange or collar for supporting the internal stator and maintaining it concentric with the casing.

7. In a horizontal turbine, the combination of a casing having an annular groove provided therein, an internal diaphragm carry-

- ing stator provided with a flange or collar engaging with the groove and in spaced relation thereto around the periphery of the flange, and at least three radially extending 5 guide pins disposed around the casing and projecting through the casing at the base of the annular groove into the flange or collar at least two of said pins being below the longitudinal axis of the casing.
- 10 8. In a horizontal turbine, the combination of a casing having an annular groove provided therein, an internal diaphragm carrying stator provided with a flange or collar engaging with the groove and in spaced relation thereto around the periphery of the flange, a plurality of radially extending guides cooperating between the flange and the groove for permitting freedom of relative radial movement therebetween and maintaining the internal stator concentric with the casing, 30 said radially extending guides comprising at least three pins extending through holes in the casing at the base of the annular groove into the flange or collar and disposed substantially uniformly around the circumference of the turbine.
- 15 9. In a horizontal turbine, the combination of a casing having an annular groove provided therein, an internal diaphragm carrying stator provided with a flange or collar engaging with the groove and in spaced relation thereto around the periphery of the flange, a plurality of radially extending guides cooperating between the flange and the groove for permitting freedom of relative radial movement therebetween and maintaining the internal stator concentric with the casing, 35 said radially extending guides comprising at least three pins extending through holes in the casing at the base of the annular groove into the flange or collar and disposed substantially uniformly around the circumference of the turbine.
- 20 10. In a turbine, the combination of a casing, a blade-carrying diaphragm, and a plurality of guide means for maintaining the diaphragm concentric with the casing, each 40 guide means permitting relative movement between the diaphragm and the casing in a radial direction only.
- 25 9. In a horizontal turbine, the combination of a casing having an annular groove pro-

vided therein, an internal diaphragm carrying stator provided with a flange or collar engaging with the groove and in spaced relation thereto around the periphery of the flange, a plurality of radially extending guides cooperating between the flange and the groove for permitting freedom of relative radial movement therebetween and maintaining the internal stator concentric with the casing, 30 said radially extending guides comprising at least three pins extending through holes in the casing at the base of the annular groove into the flange or collar and disposed substantially uniformly around the circumference of the turbine.

10. In a turbine, the combination of a casing, a blade-carrying diaphragm, and a plurality of guide means for maintaining the diaphragm concentric with the casing, each 45 guide means permitting relative movement between the diaphragm and the casing in a radial direction only.

In testimony whereof, I have hereunto subscribed my name this 27th day of May, 1924. 50

KARL BAUMANN.
